UNITED STATES PATENT OFFICE.

EDGAR E. GREVE, OF BELLEVUE, PENNSYLVANIA.

VALVE-SEAT PULLER.

Application filed July 7, 1925. Serial No. 41,962.

This invention is for a device for removing valve seats from pumps, particularly pumps used in the oil fields, and for similar operations.

5 In designing a pump, particularly one for use in an oil field, a valve seat is generally provided in the form of a ring with a slightly tapered exterior so that it can be forced into a corresponding tapered recess provided in the pump structure for the reception of the seat ring.

10 As the taper on the seat rings is very slight, and as they usually have to be forced into place, it is exceptionally hard to remove them after they have been in place for a long time, and it becomes desirable to replace them.

15 The present invention has for its principal object, to provide a device for removing such seat rings and for performing like operations.

20 Further important objects of the invention are to provide a tool for this purpose which is of simple construction and which may be easily manipulated.

25 These and other objects and advantages are attained by my invention, the nature of which may be more readily understood by reference to the accompanying drawings, 30 illustrating a preferred embodiment thereof.

In the drawings:

Fig. 1 represents a side elevation of the tool showing it in lifting engagement with a seat ring, the ring being shown in section;

35 Fig. 2 shows the lower end of the puller entering into engagement with the ring, the ring being shown in section;

Fig. 3 is a view similar to Fig. 2, showing the hooks passing through the ring; and

40 Fig. 4 is a transverse section on line 4—4 of Fig. 1.

In the drawings, 1 represents a suitable cross-bar through the center of which is slidably passed the threaded upper end of a mandrel 2. Above the cross-bar on the threaded upper end of the mandrel is an operating nut 3, by means of which the mandrel may be raised or lowered with respect to the cross-bar when the cross-bar is held stationary.

The lower portion of the mandrel, below the threaded area thereof, is squared, as indicated at 4, and below the squared portion the mandrel is flared to provide oppositely inclined faces 5 terminating at their lower ends in lips or shoulders 6.

Slidably fitted over the squared portion 4 of the shank is a transverse adjusting piece or bar 7 having laterally projecting ends or limit lugs 8 extended to a length greater than the inner diameter of an article to which the device is applied for use, thereby providing a seat or stop for positioning the device.

Straddling the adjusting piece at each side thereof, are the bifurcated upper end portions 9^a of pivoting dogs 9, pins 10 being passed through portions 9^a of the respective dogs and through the adjusting piece to provide the pivotal suspension for these dogs. 70 The inner faces of dogs 9 are constructed so as to provide large contacting surfaces with the inclined faces 5 of the mandrel. The lower end of each of the dogs terminates in a lip or ledge 9^b. The under faces of the 75 dogs are preferably rounded, as indicated at 9^c, and they are so balanced that they have a tendency to swing in toward each other when hanging free of the tapered faces 5 of the mandrel. 80

In operation, the tool is lowered through the seat indicated in the drawing as A. The bottoms of the dogs, which are at this time expanded by the mandrel, hit the top of the seat, while the mandrel continues to move 85 down through the seat. This is shown in Fig. 2. When the mandrel has moved sufficiently far down through the seat, the dogs move together and drop down through the seat, as shown in Fig. 3, until the ends 8 of piece 7 rest on the top of the seat ring. The mandrel is then lifted to move the dogs away from each other, forcing the ledges or lips 9^b under the valve seat, until further outward movement is limited by reason of the 90 ledge formation, as best shown in Fig. 1. At this time the bottoms of the dogs are on the lips or shoulders 6.

At B is designated a suitable fixed support on which the cross-bar 1 rests to hold it stationary. By turning nut 3, the mandrel may be gradually raised, lifting the valve seat out of the seat-ring recess of the pump, not shown.

It will be observed that during the operation of pulling the valve seat, the spreading movement of the dogs is definitely limited by the shoulders of the lips 9^b that hook under the seat ring. The relative movement of the mandrel with respect to the 105 dogs is also definitely restricted by the provision of the flanges or lips 6 which prefer-

ably contact, during the pulling operation, with the lower ends of the dogs.

While I have described and illustrated a preferred embodiment of my invention, it will be understood that various changes and modifications are to be contemplated within the spirit thereof.

I claim as my invention:

1. A tool of the class described including 10 an operating mandrel having a threaded portion, a tapered end portion having a pair of oppositely inclined faces thereon and a non-circular intermediate portion, an adjusting bar slidably mounted on the mandrel 15 and having a non-circular bore, a pair of dogs pivotally hung from the adjusting bar and arranged so that each of the dogs cooperates with one of the said inclined faces whereby a large contact area is provided 20 therebetween, said dogs each provided with a lifting member thereon to engage a valve

seat, said adjusting bar having a length greater than the diameters of the valve seat to engage the top surface thereof.

2. A tool of the class described including 25 an operating mandrel having a pair of oppositely inclined faces thereon, an adjusting bar slidable on the mandrel above the inclined faces thereof, a pair of dogs pivotally hung from the adjusting bar so that 30 each of them cooperates with one of the inclined faces of the mandrel whereby a large contact area is provided, each of said dogs having a lifting edge thereon to engage the under side of a valve seat, said adjusting 35 bar having projecting end portions thereon extended to a length greater than the diameter of a valve seat and adapted to engage the top surface thereof, and means for moving the mandrel.

In testimony whereof I affix my signature.

EDGAR E. GREVE.
